AIRPLANE EMPENNAGE

James S. McDonnell, Jr., Baltimore, Md., assignor
to The Glenn L. Martin Company, Baltimore,
Md.

Application June 25, 1937, Serial No. 150,247

4 Claims. (Cl. 244—87)

This invention relates in general to improvement in aircraft construction and more particularly is directed to improvement in an airplane empennage, the disclosure being directed to such 5 an airplane empennage having a novel and improved means for increasing the stability of the aircraft and for greatly improving the operation of the control surfaces.

Heretofore the rudders of an airplane of the 10 double rudder type have been attached to the fins at each end of the airplane empennage at a point which necessitates a cutback at the opposing ends of the elevator of said airplane empennage in order to enable the rudder to swing freely. This 15 has the disadvantage of causing the passage of an airflow through the cutback at each end of the elevator when the airplane is in motion, said flow being caused by the natural tendency of the air from the high pressure region below the elevator to flow to that of the low pressure region above it. The resultant upflow at the cutbacks 20 at each end of the elevator, coupled with the induced transverse flow feeding it, gives rise to a large proportion of the energy loss and wind 25 resistance and causes a decreased impress of pitching moment of the aircraft.

It is one object of the invention to provide a means for greatly improving the aerodynamic features of an airplane.

Another object is the attainment of a greatly increased impress of pitching moment of the aircraft.

A further object is the attainment of an increased impress of the energy and wind resistance of the aircraft.

A still further object is the attainment of greatly improved and stabilized operation of the control surfaces.

The above and other objects will be made apparent throughout the further description of the invention when taken in connection with the accompanying drawings, wherein like reference characters refer to like parts. It is distinctly understood that the drawings are not a definition of the invention, but merely illustrate a preferred embodiment of the invention in connection with one particular type of installation.

In the drawings:

Figure 1 is a perspective view of an airplane 50 empennage having a single elevator in normal position, showing extended tip of the fuselage.

Figure 2 is a perspective view of the structure shown in Figure 1 with lowered single elevator.

Figure 3 is a top plan view of the structure of Figure 1, showing an improved method of attach-

ing rudder to the fin in relation to a single elevator.

Figure 4 is a rear view of the structure shown in Figure 3.

Figure 5 is a front view of the structure shown in Figure 3 with rudders and single elevator in neutral position.

Fig. 6 is a perspective view of an airplane empennage having dual elevators embodying the 10 invention.

Fig. 7 is a similar view showing the elevators in lowered position.

Fig. 8 is a top plan view of the same end, and Fig. 9 is a front view of Fig. 8.

Referring now to the drawings, Figures 1 to 5, 15 inclusive, indicate an airplane empennage 1 in its entirety having a single elevator 4. The said airplane empennage is situated centrally and transversely on the fuselage of which it is a part in such manner that tip 5 of said fuselage 20 extends rearwards and under the trailing edge of stabilizer 3 to a point under the trailing edge of single elevator 4. The said single elevator extends laterally the entire span of stabilizer 3 and is hingedly mounted to its trailing edge. 25

Fins 1 and 1a are fastened respectively at each end of stabilizer 3, and perpendicularly to the span thereof in such manner that their trailing edge protrudes to the rear of the trailing edge of the said stabilizer and are adjacent to the ends 30 of the single elevator 4, the purpose of which will be understood as the description of the invention progresses.

Rudders 2 and 2a are hingedly connected by conventional means to fins 1 and 1a respectively 35 at each end of the stabilizer and it is therefore only necessary to describe the exact point at which this is done. The trailing edge of fin 1 protrudes past the trailing edge of stabilizer 3 to the point of attachment 8 of rudder 2 to fin 1 40 to which trailing edge is sufficiently extended to enable rudder 2 to swing right without interference with single elevator 4 as shown in Figure 3. At the same time the ends of elevator 4, shown in the neutral position, are substantially horizontal and adjacent to each fin and do not interfere with the movement of the rudder 2, in this manner preventing the passage of an airflow from the high pressure area below the elevator 4 45 to that of the low pressure area above the said elevator, thus giving an increased pitching moment to the aircraft. In other words, fins 1 and 1a, attached respectively to each end of stabilizer 3, form a recess in which elevator 4 moves freely.

in this manner giving increased air resistance and energy to the aircraft.

- Figures 6 to 9, inclusive, indicate another form of the invention in which an airplane empennage 5, possessing dual elevators 4a and 4b, is shown, the said elevators being hingedly connected to stabilizer 3 and separated in such a manner that they form a triangular opening at their adjoining edges. Fins 2 and 2a are fastened respectively at 10 each end of stabilizer 3 perpendicularly to the span of said stabilizer in such manner that their trailing edge extends outwardly and to the rear of the said stabilizer and adjacent to the outer edge of each respective elevator section 4a and 4b.
- 15 Rudder 2 is hingedly connected to fin 1 by conventional means. The trailing edge of fin 1 extends past the trailing edge of stabilizer 3 to a point sufficiently far to enable rudder 2 to swing right without interference from elevator section 20 4a. In the neutral position the triangular shaped surface of the extended tail 5 of the fuselage is on a level with the surface of the dual elevators 4a and 4b in such manner that said triangular shaped surface of the extended tail 25 fills a recess formed by the adjoining edges of dual elevators 4a and 4b. At the same time dual elevators 4a and 4b are substantially horizontal, the outer edges of said dual elevators, while adjacent to fins 1 and 1a, respectively, do not interfere with the movement of rudder 2. In other words, fin 1 forms a recess with extended tail 5 of the fuselage, thus permitting each elevator section to move freely in its particular recess.

The combination of extended tail 5 in correlation with the position of elevator ends 4a and 4b and fins 1 and 1a together with the extended position of fins 1 and 1a greatly improves and stabilizes the operation of the control surfaces by increasing the impress of the energy and wind resistance and serves as well to increase to a considerable degree the pitching moment of the aircraft.

I claim:

1. In combination, an airplane empennage comprising a stabilizer, a control surface hingedly connected to the trailing edge of said stabilizer having at least one end extending parallel to the direction of flight, and means closely adjacent to each end of said control surface having vertical surfaces of sufficiently greater vertical dimensions than the adjacent vertical faces of the control surface to cover the said vertical faces of the control surface in substantially all positions thereof for preventing spilling of air around the ends of the control surface, at least the

means at said first mentioned end comprising a fin mounted on said stabilizer closely adjacent said first mentioned end and substantially perpendicular to the span thereof, and a rudder hinged to said fin at a point at least substantially as far to the rear as the rearmost point of the end of the said control surface adjacent the fin. 5

2. In combination, an airplane empennage comprising a stabilizer, a control surface hingedly connected to the trailing edge of said stabilizer having at least one end extending parallel to the direction of flight, and means closely adjacent to each end of said control surface having vertical surfaces of sufficiently greater vertical 10 dimensions than the adjacent vertical faces of the control surface to cover the said vertical faces of the control surface in substantially all positions thereof for preventing spilling of air around the ends of the control surface, at least the means 15 at said first mentioned end comprising a fin mounted on said stabilizer closely adjacent said first mentioned end and substantially perpendicular to the span thereof, and a rudder hinged to said fin at a point substantially in transverse 20 alignment with the rearmost point of the portion of the said control surface adjacent the fin.

3. In combination, an airplane empennage comprising a stabilizer, a control surface hingedly connected to the trailing edge of said stabilizer 30 having its ends extending parallel to the direction of flight, and means at each end of said control surface for preventing spilling of air around the ends of the control surface, said means comprising fins mounted on said stabilizer closely adjacent 35 said ends and substantially perpendicular to the span thereof, and rudders hinged to said fins at points at least substantially as far to the rear as the rearmost points of the ends of the said control surface adjacent the fins. 40

4. In combination, an airplane empennage comprising a stabilizer, a control surface hingedly connected to the trailing edge of said stabilizer having its ends extending parallel to the direction of flight, and means at each end of said 45 control surface for preventing spilling of air around the ends of the control surface, said means comprising fins mounted on said stabilizer closely adjacent said ends and substantially perpendicular to the span thereof, and rudders hinged to said fins at points substantially in 50 transverse alignment with the rearmost point of the ends of the said control surface adjacent the fins.
